UNITED STATES PATENT OFFICE.

EDWARD E. EHRICH, OF INDIANAPOLIS, INDIANA.

APPARATUS FOR DRYING GASOLENE-CLEANED GARMENTS.

1,256,887.

Specification of Letters Patent. Patented Feb. 19, 1918.

Application filed December 18, 1916. Serial No. 137,672.

To all whom it may concern:

Be it known that I, EDWARD E. EHRICH, a citizen of the United States, residing at Indianapolis, Marion county, and State of Indiana, have invented and discovered certain new and useful Improvements in Apparatus for Drying Gasolene-Cleaned Garments, of which the following is a specification.

10 My invention relates to apparatus for drying gasolene cleaned garments and its objects are to provide a construction whereby the safe and comparatively rapid drying of garments that have been cleaned with gasolene may be carried out economically and effectively.

20 My invention employs and applies to so called cleaning methods the principles of a natural draft of the drying air created by heat movement and of the descending vapors and fumes heavier than air. To these ends my invention is embodied in the method hereinafter described and in the apparatus herein set forth and illustrated in the accompanying drawings.

25 The figure shown in the accompanying drawing is a vertical sectional view through the drying room, with the heater in partial section.

30 Referring to the drawings, 1 is a heater or furnace which may be supplied with gas, charcoal or coal as the fuel. A gas heater is herein shown. From the air chamber of this furnace leads a hot air supply pipe 2, 35 through a partition 3 which constitutes a preferable although not an essential part of the arrangement and which serves to separate the compartment in which the furnace is located from that containing the dry room. The hot air supply pipe leads into the lower part of a dry room 4. This dry room consists of a cabinet preferably made of sheet metal and entirely inclosed except for the gas inlet and exit openings and a 40 door 5 mounted in the front thereof. The cabinet is of a size that makes it capable of being readily transported and set up in any desired location within a building. It is preferably about 10 feet in height by four 45 feet wide by four feet deep, although, of course, these dimensions may be varied as desired. The drying room is preferably provided with a false bottom 6 and at its upper 50 end near the top is provided with a cross rod 7 adapted to receive hangers on which

are carried the garments to be dried after they have been cleaned with gasolene.

5 In the lower part of one of the side walls of the drying room and preferably directly opposite the hot air inlet, there is provided 60 an exit opening 8 adapted to permit the escape of the fumes of gasolene. This opening communicates with a flue pipe 9 extending vertically along one side of the drying room and at its top this flue may be provided, if 65 desired, with a removable hood 10. The connection between the drying room and the flue 9 is preferably provided by means of a laterally extended and funnel shaped body 11 which provides a comparatively large 70 area for the connecting joint between the chamber and the flue, thereby obtaining a free escape of the gasolene vapors.

75 In order to increase the heat units within the drying room the flue pipe 12 leading from the upper part of the furnace is preferably led through the drying room and emerges in an exterior extension 13 above the latter. This pipe conveys the gaseous products of combustion from the furnace 80 and through the closed pipe leading through the drying room to the atmosphere.

85 Hung by means of a suitable support mounted in the side wall of the drying room which the inlet pipe enters and directly above the inlet is a flexible valve 14 preferably formed of a piece of thin textile material and which is adapted to depend freely in front of the inlet and the function of which is to permit the hot air from the inlet 90 to pass freely into the drying room but which upon the creation of a pressure in the drying room greater than the pressure of the incoming air will be forced back against the wall over the opening, so as to close the 95 inlet and prevent the backing up of the gasolene vapors into the hot air supply pipe.

100 The apparatus above described provides means whereby what may be characterized as a quiescent or natural draft method of drying gasolene cleaned garments is provided. The furnace heats the air admitted thereto and such heated air will rise and pass out from the air chamber into the hot air supply pipe 2, owing to its tendency to 105 rise and will be drawn into the drying room merely by the natural draft. The pressure of this air due to its heat will be sufficient to blow the flexible valve away from the opening and permit the air to enter the chamber 110

where it will rise into contact with the garments hung on the supporting cross rod at the top of the garments. The gasoline vapors and fumes being heavier than air, will descend and since the top of the chamber is closed and the side walls are also closed except for the inlet and exit openings, such fumes will be forced to pass out at the exit opening 8 and thence into the flue 9 from which flue the vapors and fumes escape to the atmosphere.

It will be seen that this method and apparatus enable the employment of forced or induced draft devices, such as are customarily employed in drying gasoline cleaned garments, to be dispensed with and provides means whereby an economical method of drying the garments is obtained.

Having thus described my invention, what I claim is:

1. In an apparatus for drying gasoline cleaned garments, in combination with a furnace, a closed drying room cabinet, a hot air supply pipe leading from the hot air chamber of the furnace to the lower part of the drying room to convey the heated air by natural draft alone, means leading from the lower part of the cabinet for drawing off the gasoline vapors by natural draft alone, means for supporting garments in the upper part of said cabinet, closed means for conveying gaseous products of combustion from the furnace through the cabinet, said outlet means for the gasoline vapors and the outlet means for the gaseous products of combustion being separated and leading to different points of distribution of the gases and vapors.

2. In combination with a closed drying room cabinet, a hot air supply furnace hav-

ing communication with the drying room feeding the air thereto solely by the expansive pressure of the hot air thereof, and vapor exit means for the cabinet located only at the bottom of the room and opposite the hot air inlet, a flue leading from said exit and an automatic valve adapted to control the inlet opening and prevent the flow of vapors from the room into the air supply pipe by back pressure in the drying room.

3. In combination with a furnace, a hot air supply pipe leading from said furnace, a closed drying room cabinet to which said pipe leads to convey air under the expansive force due to its heat, a flexible freely hung automatic valve, over the inlet opening of said supply pipe, and an exit flue leading from the lower part of the drying room substantially opposite the inlet and subject only to natural draft.

4. In combination with a portable metallic drying room cabinet closed at the top and having an air inlet and a vapor outlet and a door, means at the upper part of said cabinet for supporting garments, a portable furnace for creating a supply of hot air, a conduit pipe leading from the air chamber of the furnace and communicating with the cabinet at the lower part of the latter, a vapor escape flue leading from said cabinet outlet, and a smoke pipe leading from the furnace through the cabinet.

In witness whereof, I have hereunto set my hand and seal at Indianapolis, Marion county, Indiana, this 16th day of December, A. D. nineteen hundred and sixteen.

EDWARD E. EHRICH. [L. S.]
